CIRCUIT ARRANGEMENT FOR THE SENDING OF CURRENT IMPULSES OVER
TELEPHONE LINES

Original application filed March 3, 1927, Serial No. 172,490, and in Poland April 24, 1926. Divided and this application filed May 29, 1930. Serial No. 457,358.

The sending of direct current impulses in rapid succession over long telephone lines is generally subjected to disturbances due to the electrical properties of the line, that is to say 5 its capacity, leakage, inductivity and resistance. Even if the impulse transmission takes place by interrupting and closing the line circuit at the sending place, it may thus occur that the current does not decrease down 10 to zero at the receiving place but varies, during the transmission of a series of current impulses, for instance in the manner indicated on the attached drawings, Figs. 1 and 2. Said conditions are particularly pronounced in 15 lines with a high self-induction, such as loaded lines. From a technical point of view it is impracticable to construct an impulse relay of the usual type so as to make it operate in the desired manner under such conditions. 20 The present invention relates to a circuit arrangement, whereby said disadvantage may be eliminated and the absolutely reliable operation of an impulse relay by means of direct current impulses rendered possible also 25 over lines where, on account of the electrical properties of the lines, the current variations at the place of reception follows the course illustrated in Figs. 1 and 2.

The invention is substantially characterized 30 by that in parallel with the preferably polarized impulse receiving relay an inductance is connected up the inductivity of which exceeds that of the relay so that the current through the relay, upon a decrease in the line 35 current, will be neutralized or reversed by the extra current then induced in the closed circuit formed by the relay winding and the parallel connected inductance, the relay armature being thereby shifted. This results 40 in a so called "static safety" in the relay. The relay winding is namely normally passed by a part of the line current proper whereby is ensured that the relay is brought to or held 45 respectively in its normal position in the intervals between the impulses.

The invention will be more closely described with reference to Figs. 3 and 4, Fig. 3 showing the circuit arrangement in principle 50 according to the invention and Fig. 4 its ap-

plication in a cord line or the like to which the line is connected.

In Fig. 3, L_a and L_b designate the two branches of a line which at 1 and 2 may be connected to a telephone line over which 55 direct current impulses are sent from a distant place, by way of example the subscriber's set in an automatic telephone plant. Between the terminals 3, 4 a direct current source is included. PR is a polarized relay 60 included in the line branch L_a in parallel with an inductive resistance S_i . The induction coil is assumed to have a comparatively high inductivity and a comparatively small 65 ohmic resistance in comparison with the relay PR. When the line circuit is closed a current passes through PR in the direction from 11 to 10 whereby the armature 5 is held bearing against the contact 6. The stationary current in the relay is, on account of 70 the higher resistance of the relay, comparatively small. Upon a decrease in the line current an extra E. M. F. is induced in S_i which E. M. F., if exceeding the drop of 75 voltage caused by the current through the induction coil, generates an electric current through the relay in the direction from 10 to 11 the relay armature being then shifted towards the contact 7. The relay PR is thus 80 brought to operate by the rapid current fluctuation caused by the current impulses in the relay circuit but not by the absolute value of the line current or by those comparatively slow current variations which are unable to 85 generate the potential difference required to shift the relay armature. The position of the relay armature depends, in other words, upon the current derivate

$$\frac{di}{dt} \quad 90$$

At a positive

$$\frac{di}{dt}$$

the armature bears against the normally 95 closed contact and at a negative

$$\frac{di}{dt}$$

against the normally open contact. The cir- 100

cuit arrangement shown in Fig. 3 may also be used in an ordinary neutral, i. e. unpolarized, relay. If the line current at the receiving place does not decrease to the value zero upon an interruption of the line circuit at the sending place, the extra current from the induction coil in an arrangement according to Fig. 3 will neutralize or counteract respectively the relay current so as to cause a sufficient variation in the current to de-energize said neutral relay.

The circuit arrangement shown in principle in Fig. 3 may, of course, be practically carried out in many different manners using inductances in different combinations. Instead of induction coils also electromagnetic relays may be used which, at the same time, may be used for different switching purposes.

Fig. 4 shows an application of the invention in an automatic telephone system and illustrates a circuit arrangement for connecting the impulse relay to junction lines provided with a microphone feeding bridge and also a speaking transformer and a blocking condenser, as the case may be. In the application of the invention already existing inductances in such a junction line may be advantageously used in connecting up the relay. In the arrangement according to Fig. 4 the polarized relay PR is thus connected in parallel to the one of the choke coils I_1 , I_2 included in the microphone feeding bridge, a circuit arrangement being then obtained which substantially corresponds to the arrangement according to Fig. 3. The letter A designates the subscriber's apparatus and L the subscriber's line which in ordinary manner over a pre-selector is connected to a junction line FL connected to the microphone battery over the terminals 3, 4. The junction line contains besides a speaking transformer Tr and a blocking condenser C. The portion of the junction line including the secondary winding of the transformer Tr is controlled by the relay PR over the normally closed contact 6. During impulse sending the relay PR is actuated in the same manner as that described with reference to Fig. 3 and transfers impulses from the subscriber's line to the latter portion of the junction line.

I claim:

1. A circuit arrangement for transferring selector impulses over telephone lines, especially loaded lines, comprising in combination with an impulse receiving relay, an inductance connected in parallel therewith and having a higher inductivity than that of the relay so that, upon a decrease in the line current, an extra current is induced in the closed circuit formed by the winding of said relay and said parallel connected inductance, said extra current opposing the normal relay current to such an extent that the relay armature is shifted.

2. A circuit arrangement as claimed in claim 1, characterized by the fact that said relay is a polarized relay the armature of which is adapted to be held normally in inoperative position by the line current.

3. A circuit arrangement as claimed in claim 1 for transferring selector impulses over junction lines having a microphone feeding bridge, comprising in combination with the relay, a choke coil passed by the line current and included in the microphone feeding bridge, said choke coil being connected in parallel with said relay.

In testimony whereof I affix my signature.
